UNITED STATES PATENT OFFICE

2,071,038

ARCH SUPPORTING DEVICE

John D. C. Krüger, Omaha, Nebr.

Application September 26, 1935, Serial No. 42,297

2 Claims. (Cl. 36—71)

My invention has to do with the art of arch supporting devices and the like and particularly with fibrous supports and pads.

It is the object of my invention to provide a flexible, fibrous arch support that may be built up to suit the individual needs of the user.

It is another object of my invention to provide a support of fibrous material wherein the fibers of the outer case or envelope will interlock with the fibers of pads placed therein to hold said pads in any desired position wherein they are placed.

It is a further object to provide a pad or support of the above character that is porous and which will permit air circulation therethrough.

15 A still further object is to provide a support that is soft and resilient.

Other objects of my invention will appear in the following detailed description taken in connection with the accompanying drawing where-
20 in:

Figure 1 is a plan view of my invention.

Figure 2 is a side view thereof showing the opening therein for inserting or removing pads to secure the desired thickness of the support.

25 Figure 3 is a transverse section through the device taken on line 3—3 of Figure 1.

Figure 4 is a plan view of a modified embodiment of my invention adapted to be used as a heel pad.

30 Figure 5 is a side view of the same showing a portion of the opening for insertion of pads to build up the thickness of the device.

Figure 6 is a longitudinal section through the same taken on line 6—6 of Figure 4.

35 Referring more particularly to the drawing reference numeral 10, Figures 1, 2 and 3, indicate the envelope or casing of loose fibrous material such as Luffa plant fiber. The envelope comprises two sheets of fibrous material bound together by tape 11 along their contiguous edges

40 on substantially three sides between the dotted lines 12, said tape being sewed thereto by stitches 13. An opening 14 into the envelope is provided and extends along one side between the dotted lines 12, said opening being for the insertion of a laterally tapered pad 15, preferably of the same material as the envelope, to build up the thickness of the support particularly along one side to increase the support for the foot arch. The dotted lines 16 indicate a pad partly inserted in the envelope. The edges 17 of the envelope are individually bound with tape sewed thereto by stitches 18 to prevent fraying thereof.

45 The support is placed in a shoe with the thickest portion beneath the highest part of the foot arch to support same. If necessary several pads may be used. The fibers of the material are stiff and yet soft and flexible and resilient and will adequately support the foot arch. Said fibers are loose enough to permit the circulation

of air through the device to carry away moisture and prevent excessive perspiration of the foot.

Due to the fibrous character of the envelope and the pad said pad will be held in any position in which it may be placed in the envelope by the interlocking of the fibers of said pad and envelope.

5 Figures 4, 5 and 6 illustrate a modified embodiment of my invention which may be used for a heel pad, embodying substantially the same construction and association of parts and is of the same fibrous material, namely, Luffa plant fiber.

The envelope 40 is of fibrous material bound together on substantially three sides between dotted lines 41 by tape 42 sewed thereon by 10 stitches 43. One side is provided with an opening 44 and the edges 45 of said opening are also bound with tape stitched thereto by stitches 46, said opening extending between the dotted lines 41. A tapered fibrous pad 47 is inserted in the 15 envelope with the thickest portion toward the rear to increase the thickness of the rear portion of the heel pad. A soft heel pad with an air cushion effect is thereby provided when placed in the heel portion inside of a shoe.

20 The arch supporting device and heel pad may be used, individually or together, in connection with an inner sole, not shown, of the same fibrous material. The fibers of such an inner sole will interlock with the fibers of the arch support and heel pad and hold them in position in a shoe. The interlocking action is substantially the same as that between the envelope and the inserted pad.

25 It is, of course, to be understood that the invention may be constructed in other manners and the parts associated in other relations, and therefore, I do not desire to be limited in any manner except as set forth in the claims hereunto appended.

30 Having thus described my invention what I claim and desire to secure by Letters Patent is:

35 1. In an arch support, an envelope of large, stiffly resilient fibers loosely matted together and with large air spaces between the fibers, and a pad in the envelope of large stiffly resilient fibers loosely matted together with large air spaces between the fibers, the fibers of the pad being adapted to interlock with the fibers of the envelope to prevent slippage of the pad in the 40 envelope.

45 2. In an arch support, an envelope of Luffa plant fiber, the fibers thereof being large, stiff and resilient and loosely matted together with large air spaces therebetween, and a pad of Luffa plant fiber in said envelope, the fibers of said pad being large, stiff and resilient and loosely matted together with large air spaces therebetween.

50 JOHN D. C. KRÜGER. 60
